CLAIM

An ornamental design for a multi-pot for microwave ovens, as shown and described.

DESCRIPTION

FIG. 1 shows an elevational view of multi-pot of the present invention, taken from one of the sides provided with handles;

FIG. 2 shows a front elevation view of multi-pot of the present invention;

FIG. 3 represents a lower plan view of multi-pot of this invention;

FIG. 4 is an elevational view taken from the back side of multi-pot of the present invention;

FIG. 5 illustrates an elevational view of multi-pot of the present invention, taken by the side opposed to that of FIG. 1; and,

FIG. 6 shows an upper plan view of multi-pot of the present invention.
